UNITED STATES PATENT OFFICE.

JAMES A. LOVE, OF RED SPRINGS, NORTH CAROLINA.

AUTOMATIC TRAIN-STOP DEVICE.

1,130,990.

Specification of Letters Patent.

Patented Mar. 9, 1915.

Application filed August 26, 1914. Serial No. 858,696.

To all whom it may concern:

Be it known that I, JAMES A. LOVE, a citizen of the United States, residing at Red Springs, in the county of Robeson and State of North Carolina, have invented certain new and useful Improvements in Automatic Train-Stop Devices, of which the following is a specification, reference being had to the accompanying drawings.

10 This invention relates to automatic train stop devices and has for its primary object to provide improved means for automatically cutting off the supply of steam to the engine cylinders and setting the air brakes.

15 The invention has for a further object to provide a device of the above character which is actuated by means arranged upon a semaphore arm when the latter is disposed in its danger indicating position, whereby 20 the train will be brought to a stop in the event that the engineer disregards the signal through inattention or inadvertence.

The invention has for another and more 25 specific object to provide an improved construction of cut-off valve arranged in the steam line pipe between the boiler dome and the engine cylinders, and means operated from the semaphore arm for positively actuating the movable member of said valve to 30 cut off the supply of steam.

The invention has for a still further object to provide an automatic stop device for trains, which is comparatively simple in its construction, highly reliable and positive 35 in operation and one which may be produced and installed at comparatively small cost.

With the above and other objects in view, the invention consists in novel features of construction, combination and arrangement 40 of parts as will be hereinafter referred to and more particularly pointed out in the specification and claims.

For a full understanding of the invention, reference is to be had to the following description and accompanying drawings, in which:

Figure 1 is a side elevation of a portion of a locomotive boiler showing my invention applied thereto, Fig. 2 is a section taken on 50 the line 2-2 of Fig. 1, Fig. 3 is a section taken on the line 3-3 of Fig. 2, Fig. 4 is a section taken on the line 4-4 of Fig. 2, and Fig. 5 is a section taken on the line 5-5 of Fig. 2.

55 Referring in detail to the drawings

designates the locomotive boiler which is provided with the usual steam dome 6.

7 indicates the steam line pipe leading from the dome 6 of the boiler to the engine cylinders, (not shown). This pipe is, of course, equipped with the usual throttle valve actuated from the cab of the locomotive.

8 designates the casing of the cut off valve, having ports 9 in its opposite ends to which sections of the steam line pipe 7 are connected. In this valve casing, the obliquely disposed plate 10 is arranged, and suitably secured to the casing walls. It will be noted from reference to Fig. 3 that this plate separates the interior of the valve casing into two chambers, with which the respective ports 9 communicate. A plurality of parallel slots 11 are provided in this plate which afford passage for the steam from the upper 75 chamber to the lower chamber. The longitudinal edges of the plate 10 are provided with guides 12 for a movable valve plate 13. This plate is also formed with spaced parallel slots 14, which are adapted 80 to register with the slots 11 in the plate 10. Adjacent to the opposite edges of the valve plate 13, longitudinally extending racks 15 are formed thereon. A shaft 16 is mounted in suitable bearings provided on the opposite 85 side walls of the casing 8, and to said shaft the gear segments 17 are fixed for engagement with the respective racks 15.

18 designates the air supply tank from which the air is supplied for the operation 90 of the brakes. A pipe 19 connects this tank to the train line pipe 20. A second pipe 21 also extends from said tank to the engineer's valve in the cab of the locomotive. A vertically disposed lever 22 is fulcrumed at its 95 lower end as at 23 upon a suitable rack 24 mounted upon the locomotive boiler. This lever carries a pair of spring pressed locking members 25 for engagement in the respective notches 26 provided in the upper 100 edge of the rack plate 24. In the pipe 19, a rotatable valve member 27 is located; said member being provided with a port 28 through which communication may be established between the air tank 18 and the 105 train line pipe 20. To one end of this rotatable valve member an arm 29 is secured and is provided with a slot 30. A similar arm 31 is also fixed to one end of the shaft 16 and is provided with a slot 32. To the 110

lever 22 spaced pins 33 are fixed. These pins are disposed in the slots 30 and 32 of the arms 29 and 31 respectively.

The semaphore arm indicated at 34 has a rod 35 secured thereto, and this rod, when the arm is set in its danger indicating position is disposed in the path of the upper end of the lever 22.

From the above description taken in connection with the accompanying drawings the operation of the device will be understood as follows: Assuming that the semaphore arm has been set against the train, and that the engineer disregards the signal and attempts to run the train past the station, the rod 35 will engage the upper end of the lever 22 and move the same. In this movement of the lever, one of the pins 33 thereon throws the arm 31 and thereby rocks the shaft 16. In this rocking movement of the shaft the gear segments 17 thereon shift the valve plate 18, so as to dispose the slots 14 thereof out of register with the slots 11 in the stationary plate 10. The supply of live steam from the dome 6 to the cylinders of the engine is thus cut off. The continued movement of the lever 22 operates through the medium of the other pin 33 thereon to rotate the valve member 27 in the pipe 19 and thereby open communication through said pipe between the tank 18 and the air line pipe 20, so that the brakes are applied. In this manner the train will be quickly brought to a stop and a collision or wrecking of the train avoided. In view of the extreme simplicity of my invention it will be appreciated that the same is reliable and positive in its operation. The device can also be inexpensively constructed and installed without necessitating any material alterations in the train equipment.

While I have above described the preferred form, construction and arrangement of the several elements employed, it will be

understood that the device is, nevertheless, susceptible of considerable modification therein, and I therefore reserve the privilege of resorting to all such legitimate changes as may be fairly embodied within the spirit and scope of the invention as claimed.

What I claim is:

1. The combination with an engine throttle valve, of an operating lever for said valve fulcrumed at one of its ends, relatively stationary means adapted to engage the other end of said lever in the movement of the train in either direction to actuate the lever and close the valve, and means for latching said lever against movement after the throttle valve has been closed.

2. The combination with an engine throttle valve provided with a slotted arm, of a lever fulcrumed at one end and provided with means loosely engaged in the slot of the valve arm, and normally stationary means adapted to engage and move said lever in the movement of the train in either direction to actuate said throttle valve and close the same.

3. The combination with an engine throttle valve and an air controlled valve, each of said valves being provided with a slotted arm, of a lever pivotally mounted at one end and normally disposed in a vertical position, spaced pins on said lever engaged in the slots of the respective valve arms, stationary means adapted to engage said lever in the movement of the train in either direction to move the lever and simultaneously close said valves, and means for automatically locking the lever at the end of its movement to maintain the valves in closed position.

In testimony whereof I hereunto affix my signature in the presence of two witnesses.

JAMES A. LOVE.
